UNITED STATES PATENT OFFICE.

JOHN A. MANTZ, OF JERSEY CITY, NEW JERSEY.

DESIGN FOR A JET FOR LIME-LIGHTS.

SPECIFICATION forming part of Design No. 29,149, dated August 2, 1898.

Application filed July 21, 1897. Serial No. 645,475. Term of patent 7 years.

To all whom it may concern:

Be it known that I, JOHN A. MANTZ, of Jersey City, in the county of Hudson and State of New Jersey, have invented and produced 5 a new and original Design for a Jet for Lime-Lights, of which the following is a full, clear, and exact description.

Reference is to be had to the accompanying drawings, forming a part of this specification, 10 in which similar characters of reference indicate corresponding parts in both figures.

Figure 1 is a perspective view of a jet showing my design, and Fig. 2 is a plan view of the same.

15 The leading feature of the design consists in

the configuration shown, the same comprising a boss B, from one side of which extends the bend A' of the base portion A, and from the top of which boss rises upwardly and forwardly the spout C, terminating in the contracted mouth D. A minor feature of the design consists in a flat base-plate E for the base portion A and the boss B.

I claim—

The design for a jet for lime-lights herein 25 shown and described.

JOHN A. MANTZ.
